UNITED STATES PATENT OFFICE.

NICOLAS BENOIT GRILLET, OF NEUILLY, FRANCE, ASSIGNOR TO SOCIETE POUR LA FABRICATION DE LA SOIE "RHODIASETA," OF PARIS, FRANCE.

APPARATUS FOR THE MANUFACTURE OF ARTIFICIAL THREADS OR FILAMENTS.

Application filed March 5, 1924. Serial No. 697,029.

To all whom it may concern:

Be it known that I, NICOLAS BENOIT GRILLET, residing at Neuilly, Seine, France, a citizen of the Republic of France, have invented certain new and useful Improvements in Apparatus for the Manufacture of Artificial Threads or Filaments, of which the following is a specification.

The present invention relates to improvements in processes and apparatus intended for the manufacture of artificial filaments of all kinds constituted by a single fibre or, on the contrary, by the union of several fibres obtained by flowing or spinning, in a gaseous medium, whether heated or not, of a more or less viscous fluid of suitable composition, comprising essentially:

(1) A solvent or solvent mixture (A), volatile in the operating conditions which are selected for spinning the said fluid.

(2) A body or mixture of bodies (B), suitably selected, non-volatile in the operating conditions adopted for spinning, which, when freed by evaporation of the liquid or mixture of liquids (A), constitutes the substance of the artificial filament issuing after spinning, (B) being constituted, for instance, by an ether, an ester, or another derivative of cellulose, alone or mixed with other ethers, esters, or cellulose derivatives, or else by a derivative or mixture of derivatives of cellulose with substances adapted to impart plasticity or non-volatile solvents of the said derivatives, the mixture (B) being, if desired, such as also to comprise in every one of the above cases one or more definite bodies, added for various purposes, which will remain in the completed filament or which will be subsequently removed, for instance, to dye it, to dress or finish it, or give it any required useful properties in view of its ultimate use.

In such processes the spinning apparatus properly so-called is constituted by a cage or cell, closed or almost closed, within which is placed at one of its extremities the spinning device or spinning die, which comprises essentially holes or orifices the shape, number and diameter of which are suited to the kind of threads or filaments which it is desired to manufacture, the exit orifice or orifices of this or these threads or filaments

being situated at the other extremity of the cage or cell.

In each cell there passes a current of air or of any other gaseous medium intended to enhance the evaporation of the volatile solvent or solvent mixture (A) and to carry away outside of the cell the corresponding vapours, to conduct them, for instance, if desired, to a suitable apparatus for the recovery of the said volatile solvent or solvents.

This gaseous medium enters into the cell through the orifice or orifices through which issue the thread or threads or filament or filaments, or by openings of suitable shape and dimensions provided in the portion of the walls of the cell which is in the neighborhood of the said issue orifice or orifices. It passes through the cell in the opposite direction to that of the threads or filaments which are being manufactured, and issues from the cell by openings suitably provided in the portion of the walls of the cell which is in the vicinity of the spinning device. The said gaseous medium is either aspirated from or forced through the cells by means of any suitable device or propelling apparatus known and in common use.

The said gaseous medium is preferably heated by any suitable means, either outside the cell, before entering the latter, or in the cell during its passage therethrough, or by these two methods simultaneously, the heating being carried out so as to obtain a suitable regular temperature in the whole of the cell; however, if desired, different temperatures may be maintained at different levels in the cell, as may be suitable for any desired purpose.

The fluid to be spun is brought to the spinning dies at a suitable pressure and by any known means, after having passed through, if thought advisable, any desired apparatus such as filters, regulators for the temperature or the pressure, and the like. It issues by the orifices of the spinning dies and passes through the cell in the opposite direction to the aforesaid current of the gaseous medium, either in a natural manner, when the spinning takes place in a downward direction, or by any suitable arrangements in the other cases. As the vola-

tile body or mixture of bodies (A) gradually evaporates, the thread or threads, filament or filaments, issuing from the orifice or orifices of the spinning device, solidify 5 and acquire consistency. As soon as this consistency is sufficient, and particularly as soon as the threads or filaments are dry or nearly dry, they are ready to be made to pass out of the cell by any suitable orifices, 10 after having united them, if required, into one single thread or filament. From this point, this or these threads or filaments proceed to any further desired apparatus or plant in order to receive any suitable treatment, such as, for instance, stretching, impregnation with any substance for any desired purpose, twisting, bobbining, etc.

The whole or part of the said treatments may, however, take place either entirely or 20 partially within the cell, before the threads or filaments issue therefrom.

Finally the cell may be provided with any accessory apparatus or plant which may be necessary or desired, either to facilitate the 25 spinning or to allow the control and the regulation of the process, or for any other purpose, such, for instance, as those described for the sole case of the downward spinning in the co-pending application No. 30 667,872 of 11th October, 1923, or in any other suitable or usual and known apparatus or plant.

The present invention is more particularly applicable to the industrial manufacture 35 of artificial threads or filaments of all kinds by the process called "dry spinning," the principal characteristics of which are indicated by the foregoing description.

In this industrial manufacture a very 40 large number of cells of the type described above is, of course, employed. They are usually arranged in such a way as to occupy the least possible area of the shed, every one of them being employed in the manufacture 45 of a similar commercial grade of products, or else, more frequently the cells being distributed in a certain number of groups of cells, more or less important, each one employed in the manufacture of a different kind.

By "similar commercial grade" is meant 55 not only products of the same kind, such, for instance, as silk, wool, horse-hair, or any other artificial filament, but for each 60 of these kinds products of the same commercial quality are meant, and particularly having the same number of fibres of the same standard, excepting naturally such qualities as torsion, dyeing, preparation, etc., which are, or may be, given to the threads or filaments after their complete formation and outside the manufacturing cell.

At is natural, it will be necessary that the 65 commercial quality of the products manu-

factured by each cell of the same group be as uniform as possible, not only in space, that is, for the several cells of the group, but also in time, that is, for the same cell, at the various moments of the manufacture.

The standard and the qualities of each elementary fibre which is manufactured depend on a great number of variable factors, among which may be mentioned: the composition of the fluid to be spun, its viscosity, and therefore its temperature, the form and the dimension of the spinning die or dies, the spinning pressure, the speed of spinning, and therefore the tractive efforts which are exerted upon the thread at the moment of its formation, and, finally, to a very great extent, the nature and the properties of the medium in which spinning takes place, particularly at the beginning, when the elementary fibres are still plastic and devoid of solidity, and the time during which this medium acts, that is, the length of the cell. This medium, that is, the gaseous atmosphere selected, exerts a special influence by its temperature and its rate of flow, apart from any chemical action.

The temperature of the said atmosphere affects the viscosity of the fibre being formed and therefore the shape which is assumed by this fibre; it also affects the speed of evaporation, and therefore the speed of formation of the fibres. The rate of flow will affect the speed of evaporation on one hand for a well-known purely mechanical reason, on the other hand in determining, together with the temperature, the successive proportions of volatile solvents in the said atmosphere, and, therefore, its evaporating properties.

All these variable factors on which depend the standard and the properties of each elementary fibre are not, of course, independent of one another, and it would be possible, at least theoretically, to regulate or modify one or some of them, so as to compensate the variations of one or of some others, and to obtain, in spite of these variations, a uniform manufactured product. The only practical and known means for ensuring the required uniformity is, however, to maintain as strictly constant as possible, in space and in time, all the conditions governing the spinning of a cell of the same group.

The cells are preferably uniform in shape and dimensions, the spinning device or the whole of the spinning dies of each cell being similarly placed and as identical as possible. The fluid to be spun utilized for feeding the group is of constant composition and is brought to the spinning dies by means of any suitable usual or known apparatus or arrangement, under a regular and constant pressure and either at a constant temperature or at a temperature such that the vis-

cosity of the said fluid is constant. Finally, it will be spun at a constant speed in a medium of constant composition and temperature, constant in time and for regions simi-

larly placed, that is, occupying the same level in each cell of the group, the said medium being either forced through or aspirated from the cell with a rate of flow which is maintained constant and uniform.

10 The present invention relates more particularly to improvements in the usual or known arrangements in order to ensure the uniformity of the heating of the gaseous medium before or while passing through 15 all the cells of the same group, together with the regularity of the rate of flow of the said medium through the said cells. This result, to my knowledge, has hitherto not been obtained, no one having succeeded in ensuring 20 the automatic regulation of the heating, in a simple manner, simultaneously in a very great number of enclosures.

The idea which occurs quite naturally is to regulate individually the heating in each 25 of these chambers by means of suitable taps or any other devices. This regulation, however, is laborious, it uselessly occupies a great number of hands, and cannot be, in any case, strictly uniform. Former operators have 30 also been satisfied with the heating in series of a relatively small number of these chambers with the same heating device (coil with steam or hot water circulation, for instance), or with other similar methods. In this manner of heating in series, mentioned above, it 35 is evident that the number of heat units supplied to the apparatus situated at the end of the piping is very inferior, for an equal heating surface, to the number of heat 40 units received by the apparatus at the beginning of the piping.

Generally no account is taken of this irregularity or else it is diminished by suitably modifying the intensity of the heating arrangement for each chamber, according to 45 its rank in the series of chambers to be heated, which, for a great number of chambers, complicates extremely the heating installation.

50 I have found that one can obtain in a very simple manner a heating which is as strictly uniform as may be desired, in a number, however great it may be, of similar chambers provided with identical heating apparatus, by operating according to the principles mentioned hereafter, which I shall first set forth in respect of a heating coil with 55 hot water circulation. This hot water is provided, for instance, with a suitable tank or reservoir, where its temperature is maintained uniformly at the required degree by 60 any usual or known means.

If the heating coils of all the chambers are placed in series on this hot-water tank, the chambers which are situated farthest

from the reservoir will receive, as has been explained above, less heat units than the chambers which are nearer to the said reservoir.

A compensation to these differences in the 70 heating of chambers placed at different ranks is obtained by providing them with a second heating arrangement, arranged in series, identical with the first (the coils having the same dimensions) which is the seat of a current flowing in the opposite direction to the former, either a current of hot water at the same temperature as for the first heating and having the same rate of flow, or, more simply, by the hot water itself which has 75 been used for this heating and which returns in this manner to the head of the series of chambers after having passed through each of them twice in opposite directions.

The scientific study of the problem shows 80 that the compensations will not be absolutely strict, but that the maximum departure is independent of the number of chambers to be heated and is a function only of the differences between the temperature of the 85 heating water at the beginning and at the end of its circuit and the temperature, supposed constant, of the chambers to be heated. It shows, moreover, that whatever may be 90 the latter temperature, the difference between the extreme temperatures of the heating water may always be chosen so that the maximum departure from the average 95 heating may be inferior to any desired value.

Whatever may be the value of these theoretical considerations, I have actually verified in practice that, for a very great number of cells arranged according to the above principles with double heating coils identical with one another, and designed so as 100 to provide an ample allowance, for all the cells the heating is practically strictly uniform for a difference of temperature between the incoming and the outgoing heating water approximating to 5 to 10° C. for 105 instance.

The water having been used for the heating, can of course be utilized again, and, for instance, may go back to the feed reservoir 110 where it will receive by any suitable means only the heat units lost during its journey, so that the important condition mentioned above that only a relatively small difference 115 can be allowed between the extreme temperatures does not involve any supplementary 120 consumption of fuel.

It is superfluous to insist upon the efficiency, the certainty and the simplicity of installation or of working of the arrangement which I have discovered compared 125 with all the processes hitherto known or put into practice, but it will be understood that the form under which this arrangement will be put into operation may depart considerably from that which has been described 130

above for the clearness of the demonstration only, without departing from the spirit of the present invention.

Instead of water, one may use for this 5 heating any liquid, any solutions, or even any fluids, gas or vapor, which may be deemed suitable or desirable. The said fluids may be used over again as it has been said above or in any other manner, in whole 10 or in part, or, on the other hand, it may not be so used again. It may be heated at any desired temperature: electrically, by a flame, hot gases, steam coils or steam bubbling, or by any other suitable, usual or known 15 means. It may be purified or not, or may be mixed or not with any substances, for instance, to avoid its thickening or the formation of deposits, or for any other reason.

20 The heating plant for the said fluid, outside the group of chambers, may be of any kind and may comprise any apparatus or necessary arrangements which may be desired, for instance, for storing reserves of hot or cold fluid, fresh or already used, for 25 controlling and regulating its rate of flow through the group or its temperatures, avoiding any unnecessary heat losses, or for any other purpose.

30 The said installation may be single for the whole group or, on the contrary, the latter may comprise, if it is desired, several similar or identical installations. All the chambers of the group may be in series upon the same installation, or, on the contrary, may be distributed in sub-groups of chambers in 35 series, these sub-groups being themselves arranged in parallel on the said installation or installations and all usual or known 40 precautions being taken, with the help, if necessary, of any useful accessory apparatus or devices, to ensure in spite of this the uniformity of the heating in all the chambers of the group.

45 On the contrary, two or more groups of cells employed for different manufactures may be connected as stated above upon the same heating installation, arrangements being made by means, if necessary, of any apparatus or suitable accessory devices, 50 known or usual, so that each of these groups should receive the rate of flow of heating fluid which is useful for the best possible working of the manufacture in which it is employed.

55 The fluid utilized for the heating may be driven at any desired speed through the heating coil by any means or suitable usual or known apparatus, for instance, mechanical, such as pumps, or physical, such as thermo-siphons, or both mechanical and physical, or based on any other principle.

60 The heating coils, identical for each chamber, may be cylindrical, or, on the contrary, may have any other suitable or desired shape. They may be replaced by any

similar arrangement, such as heating jacks or any other arrangement, be provided with vanes or any other radiating members for heat, and be placed in such zones of the chamber which may be deemed advisable. Similar arrangements may, of course, be used for cooling instead of heating.

65 In the manufacture of artificial threads or filaments which specially concerns me, the above described arrangement which I 70 have discovered may be used as well for the heating of the groups of cells as for the heating or cooling of the selected gaseous atmosphere, either before its entrance into the cells, or after it has come out of same, 75 whatever may be the purpose in view in performing these operations.

80 The use of these arrangements will therefore permit, all other spinning conditions remaining the same, the obtainment at the 85 exit of each of the cells of the group of a gaseous atmosphere of strictly constant composition and temperature, which will allow the regulation of its rate of flow in a manner also strictly uniform, as will be described hereafter.

85 Concerning the regulation of the rate of flow, when it was not neglected, which could only lead to unsatisfactory results, as I have shown above, it has hitherto been 90 performed by means of regulating arrangements individually provided for each cell. These arrangements, very simple apparently, so that they presented themselves at once to the mind, have in practice serious 95 inconveniences.

100 Although it is obviously easy to regulate two or a small number of taps placed upon pipings connected to the same general collector, in such a way that the gaseous flow 105 through each of them is approximately the same for all, it is evident that the problem becomes much more delicate and laborious to solve if it is a question, as is the case 110 industrially, of a very great number, for example a thousand or more taps, to be regulated in a uniform manner, even if these thousand or more taps are each provided with a flow meter, the thousand or more flow 115 meters being carefully compared and standardized.

120 In spite of the high cost of such an installation, it will be very difficult to obtain by this process a strictly uniform regulation, particularly if the temperature of the 125 gaseous medium issuing from the cell is not strictly the same for all the cells of the group and, moreover, during the course of manufacture itself, it will not be possible to avoid irregularities caused by the untimely operation of one or several taps.

130 It is possible to obtain in a more economical manner a regulation of the rate of flow as uniform and as constant as may be desired, and this without laborious manipu-

lation and for a group of cells as may be desired, by observing the following directions which I shall first set forth in the supposition that the gaseous atmosphere is 65 aspirated through the cell.

Each of the cells of the group is connected by an individual pipe or passage to a collector which may be either a general collector, common to the whole group, or a 10 secondary collector, common to a portion of the group only, the secondary collectors being themselves connected to collectors of a more general kind, and so on, so that all the groups are finally in communication with a 15 general collector to which are connected the aspirating device or devices associated with the said group of cells.

It will be essential that all these individual passages, secondary or general, have a 20 large diameter, so that the loss of head produced by them is negligible, or very small, compared to the difference of pressure obtained by means of the aspirating device.

In this manner the fall of pressure will 25 be the same in the individual outlet pipings conducting from each cell to the corresponding collector. If this group is very important and therefore the losses of head in the above described system of piping not negligible, 30 although very small, the same result will be obtained, namely, uniform fall of pressure at the exit of the cell for all the cells of the group, by a suitable arrangement, for instance one which is perfectly 35 symmetrical, of this system of piping, or by any other suitable usual device or any device known by technical experts. With the above described arrangement, and if the inlet orifices to each cell for the selected gaseous 40 medium have been also designed with an ample allowance, together with the section of the parts or apparatus through which the said medium may be made to pass for various purposes before entering the cell, the 45 rate of flow of this medium through each cell will be strictly the same for all the cells of the group. It may be adjusted to any desired value by creating in the general collector, by any suitable or known means, exactly 50 the fall of pressure which, taking into account the dimensions of the plant, precisely corresponds to this desired rate of flow.

Without excluding the possibility of proceeding as described above, I prefer, however, to create in the general collector a fall of pressure which is greater or much greater than that which would be necessary according to the above method. The desired rate 55 of flow in each cell is then, in this latter case, obtained by providing the individual outlet piping of each cell with individual devices causing a loss of head. These devices may be of any kind, for instance, they may be

constituted by tubes of small diameter and of definite length inserted in the said outlet individual pipings or else definite constrictions of the said pipings or else diaphragms constituted by holes of definite diameter pierced in plates of definite thickness and placed in said pipings or else, finally, any other suitable usual or known system.

The said arrangement is constructed or arranged in such a manner as to create, for the rates of flow approximating to a desired 70 rate, a notable or even very marked loss of head in comparison with the loss of head for the same rate of flow corresponding to the whole of the remaining pipings for the gaseous medium or the variations of the 75 losses of head caused by any manipulation which may be performed on the gaseous stream or, more generally, to any cause 80 whatever.

In this manner, the variations in the design of the said whole of the pipings, unavoidable in practice when it concerns a group comprising a very large number of cells, will only have an importance which 85 may be as small as may be desired on the 90 course of the process which is the object of the present invention.

These arrangements may be strictly identical for all the cells (for instance, diaphragms with holes of the same diameter pierced through plates of the same thickness) if the above indications have been borne in mind. They can also differ, for instance, for one or some portions of the group, in order to allow for the different 95 losses of head in the pipings corresponding to this or these portions of groups and resulting either, for example, from a non-strictly symmetrical installation, or from any 100 other cause.

It is well understood that the loss of head caused by the individual devices above provided for each cell, and therefore also the fall of pressure to generate in the general collector, will be selected in such a manner that, bearing in mind the importance and the irregularities of the whole of the pipings of the group or the possible irregularities in the working of the aspirating apparatus used, the variation of the rates of flow, either in the same time for the same cell, or in space for all the cells of the group, will not, in the most unfavourable case, exceed the required value, as determined in advance, whatever may be the gaseous rate of flow 110 which passes through the cells, bearing in mind all the contemplated changes in manufacture.

In all cases it is an extremely simple matter to vary these rates of flow to pass from one manufacture to another or in any other desired purpose, since it is sufficient for this 115 to cause a variation of the fall of pressure 120

created in the general collector by the corresponding aspirating device or devices, by any usual or known means.

The arrangements to be adopted will be 5 exactly similar in the case when one desires to drive the selected gaseous medium through the cell instead of aspirating it. It is evidently sufficient to replace in the above description "outlet" by "inlet," "fall of pressure" by "pressure," and "aspirator" by "air-pump."

The apparatus used for generating the gaseous stream through the cell may be of any kind; it may be connected to a single 15 group, or, on the other hand, may be connected to several groups each of which is provided with a suitable general collector, by any suitable usual or known means or arrangements.

20 The pipings connecting the cells to the pumping arrangement may be provided with any suitable accessory organs to fulfil the required purposes. For instance, in the case of the generation of the gaseous stream

25 by aspiration, if it is desired to recover the volatile solvents contained in the gaseous medium issuing from the cells, the installation necessary for this recovery is preferably located after the aspirating devices,

30 but, in order to perform this recovery in good working conditions, the said pipings may be then provided with any suitable arrangements, for instance, for cooling or otherwise for any desired purpose. One

35 may also in this case foresee the possibility of isolating any cell or any group or any portion of a group of cells which is momentarily not in operation for any reason, for instance, for repairs, this being obtained

40 by means of any suitable usual or known arrangement. If the arrangement which causes the loss of head is a diaphragm introduced in a joint of the individual pipings, one may, for instance, arrange that the plate

45 in which the whole of this diaphragm is pierced, is adapted to slide in the joint so as to block it.

If the gaseous medium issuing from the 50 cells and carrying volatile solvents is inflammable or explosive or adapted to become so, one may introduce, if convenient, on the individual outlet pipings of each cell, or on the secondary or general collectors, safety

55 devices of any known type, but preferably not causing any loss of head except losses of head which are very small or constant. These devices may comprise, for instance, metallic gauzes in combination with sudden changes in the shape of the section or in the

60 direction of said pipings and with portions of their wall which are either fragile or mobile, adapted to come apart or to open in the case of fire or explosion within said

65 pipings to bring their contents in ample contact with the surrounding atmosphere.

In the case of generation of the stream by forcing the gaseous medium through the cell, this gaseous medium may be submitted, between the pump and the cells, to any suitable or desired treatment such as drying, 70 moistening, heating, or cooling, or other.

In both cases, the gaseous medium may or may not be sent again through the cells in whole or in part after recovery of the solvent, or after having been freed from 75 the whole or part of the latter, by any suitable means or process, and restored to the condition where it is desired to use it in normal circumstances by means of drying or, on the contrary, moistening, heating or 80 cooling, partial exhaust to the atmosphere and in production of new gaseous medium or generally any other suitable operation.

Temperature equalizers may be provided 85 if desired and according to any known or suitable arrangements, between the warm gaseous medium issuing from the cells and the whole or part of the medium intended for the supply of the said cells.

It is understood that the arrangement 90 which constitutes the object of the present invention may be used, whatever may be the type of the cells adopted, their form and the manner in which they are constituted or united in groups, the number and 95 the dimensions of the elementary fibres, in each thread or filament, as also the nature of the cellulose derivatives, of the solvent or solvent mixture, and of the various additive substances which constitute the fluid to be 100 spun, the nature of the composition of the atmosphere in which the spinning takes place, and whether the spinning is performed upwards or downwards or in any other manner.

The treatments to which the threads or 105 filaments which have been manufactured are subjected, after their formation, either in the cells or outside the latter, such as supplementary stretching, impregnation by any 110 compound and for any desired purpose, torsion or winding or any other treatment, may be of any kind and even vary from one portion to another of the same group of cells.

In order to illustrate the present invention, I describe hereafter its application to a group of 500 cells in each of which a solution of cellulose acetate in a mixture of acetone and methyl alcohol is spun upwardly to form artificial silk in a current of air from the atmosphere of the shed, aspirated through the cells, which are internally heated by circulation of hot water.

It will be understood that this description 125 is given as an example only, and does not in any way limit the invention as described above.

In the appended diagrammatic drawings:—

Fig. 1 represents in plan the heating diagram for the group, the cover of the upper half group of cells being withdrawn to show in plan the arrangement of the heating elements, the distribution piping being indicated for one half of a group only, and all accessory organs being supposed omitted;

Fig. 2 represents, in plan and in elevation, the detail of a heating element;

Fig. 3 represents in plan the diagram for the whole of the pipings for the aspiration of the air through one half of a group (not shown);

Figs. 4 and 5 represent the front elevation and end view of a portion of a group, showing in a more detailed manner the application of the heating and aspirating arrangement to one cell.

1, 1, 1 . . . represent single parallelopiped shaped cells, united to one another so as to form partial groups 2, 2, 2 . . . of 50 cells. In each cell 3 is a glass door allowing the spinning performance to be supervised, and to remedy all incidents of manufacture. 4 represents the spinning die of each cell, which die is supplied with the fluid to be spun by means of any suitable device. 5, 5 . . . are the elementary fibres produced by each hole, orifice or spinneret of the spinning die, and united into one thread 6 which issues from the cell by a suitable orifice 7 to proceed to any further suitable apparatus or plant (not shown); 8, 8 . . . represent return heating elements, all identical among themselves, for all the cells, and constituted by semi-cylindrical double-walled vessels, illustrated with greater details in Fig. 2.

The heating elements of two neighbouring cells are connected together, internally of the cell, by short pipes 9 of large diameter, passing through their common wall, in any easily conceived manner.

The series of elements for the outgoing hot water are connected to the series of elements for the ingoing water by elbows 10, 10 . . . external to the cells, situated at the end of the sub-groups of cells opposite to the hot water inlet. These elbows are very carefully lagged with a heat insulating material.

The hot water issues from a reservoir 11, very carefully lagged with a layer 12 of heat insulating material, and provided with a thermometer 13, a level indicator 14, an overflow 15 and any other desired auxiliary apparatus.

Preferably, condensation water, or carefully purified water, will be used to avoid deposits.

The water is heated in the reservoir 11 by means of steam jets 16, the output of which can be regulated by cocks 17. It proceeds to the several sub-groups of cells by the systems of piping 18, its supply being ensured by a pump 19, placed at the head of

the piping system, and the output of which is adapted to be varied.

Perforated diaphragms 20, the orifices of which are carefully determined, are placed at the head of the piping of each sub-group heating system, so that the rate of flow of the water is the same in all these systems, or else one uses for this purpose any other simple device. At the end of its journey, the water is sent back in the reservoir 11 by the piping system 21. These piping systems 18 and 21 are very carefully coated with a thermal insulating lagging. Thermometers 22 are placed at the inlet and at the outlet of each sub-group heating system; and also, if desired, in the cells, in order to allow the control of the temperature at various levels. The latter thermometers may be fixtures or removable.

The desired variations of the heating of all the cells of the group are very simply obtained by altering to this end the temperature of the water of the reservoir 11.

The air of the shed enters in each cell by the outlet orifice 7 of the thread, and also by the orifices 23, 23 . . . provided in the portion of the walls of the cell which is in the vicinity of this outlet 7.

After having become charged with vapours in the course of its journey through the cells, the air issues by the pipings 24, 24 . . . comprising each a joint 25 in which is situated a diaphragm 26 of suitable design, the same for all the cells, which diaphragm is adapted to slide to close the joint.

The pipings 24 end in secondary collectors, 27, provided with pressure gauges 28 and any other desired regulation and control apparatus. These secondary collectors 27 are connected to a general collector 29 by means of pipes 30 which comprise a fire safety device 31, constituted by metallic gauzes 32 and paper discs 33 supported by metallic gauzes 34, in combination with sudden changes in the direction of the pipings 30, as shown in Fig. 3.

All these pipings or collectors 24, 27, 29, 30 have an ample allowance of diameter, to ensure the required rate of flow of air without noticeable loss of head, as has been described above.

An aspirating fan with adjustable output 35 creates, in the general collector 29, the desired fall of pressure, the latter being measured by means of the pressure gauge 36.

What I claim and desire to secure by Letters Patent is:—

1. In the manufacture of threads by spinning a viscous fluid containing a volatile solvent into elementary fibres in a heated gaseous current passing through a cell, means for causing the said gaseous current to pass through the said cell and means for regulating the evaporation of solvent in a

- group comprising a great number of cells by acting on the temperature of the gaseous current, said means comprising a double series of temperature controlling elements identical to one another for the whole of each group and for each cell of the group, a current of temperature controlling fluid passing in each said series of elements in opposite directions.
5. In the manufacture of threads as claimed in claim 1, means for further regulating the evaporation of solvent in a great number of cells by creating at the head of the system through which the said gaseous current flows a fall of pressure greater than that necessary in each cell, said means comprising devices interchangeable but non-adjustable individually causing a known loss of head placed in the individual piping of each cell.
10. In the manufacture of threads as claimed in claim 1, and means for controlling the temperature internally of the cells.
15. In the manufacture of threads as claimed in claim 1, and means for controlling the temperature externally of the cells.
20. In the manufacture of threads as claimed in claim 1, and means for controlling the temperature internally and externally of the cells, simultaneously.
25. In the manufacture of threads as claimed in claim 1, and means for controlling the temperature by fluid from one source at the head of one of said series of elements passing twice through each enclosure, once in the outgoing portion of the circuit, and again in the return portion of the circuit.
30. In the manufacture of threads as claimed in claim 1, and means for controlling the temperature by fluid from two sources, one at the head of each of said series of elements, the streams in the two series flowing in opposite directions.
35. In the manufacture of threads as claimed in claim 1, the temperature-controlling elements being designed so that the difference between the temperatures of the fluid utilized for temperature control at the inlet and outlet of the group of chambers or cells is from 5 to 10° C.
40. In the manufacture of threads as claimed in claim 1, an arrangement of chambers or cells such that the enclosures whose temperature is controlled by the same double series of elements are grouped in sub-groups branched on a single temperature-controlling system.
45. In the manufacture of threads as claimed in claim 1, means for causing the passage of the said heated gaseous current through the said enclosures comprising pipings designed for a rate of flow greatly in excess of that required so as to render the loss of head in said pipings negligible in comparison with the head causing the said current.
50. In the manufacture of threads as claimed in claim 1, and means for regulating the rate of flow of the said gaseous current by adjusting the head causing the said current.
55. In the manufacture of threads as claimed in claim 1, and means for regulating the rate of flow of the said gaseous current whereby the head causing the said stream is maintained constant and each cell provided with devices adapted to cause a known loss of head.
60. In the manufacture of threads as claimed in claim 1, and means for regulating the rate of flow of the said gaseous current whereby the head causing the said stream is maintained constant and each cell provided with devices adapted to cause a known loss of head, said devices being identical for all the cells of a group.
65. In the manufacture of threads as claimed in claim 1, and means for collecting the gaseous medium passing through the enclosures so that it may be used again.
70. In the manufacture of threads as claimed in claim 1, means for recovering the vapors carried by the gaseous medium, and means for collecting said gaseous medium so that it may be used again.
75. In the manufacture of threads as claimed in claim 1, accessory means for ascertaining the temperature and rate of flow of the gaseous current in any desired position in the group of enclosures and in individual enclosures.
80. In testimony whereof, I affix my signature.

NICOLAS BENOIT GRILLET.
